JAMES F. GUTHRIE, OF SOMERVILLE, MASSACHUSETTS.

Letters Patent No. 96,911, dated November 16, 1869.

IMPROVEMENT IN CASTING COPPER TUBES.

The Schedule referred to in these Letters Patent and making part of the same.

To all whom it may concern:

Be it known that I, JAMES F. GUTHRIE, of Somerville, in the county of Middlesex, and State of Massachusetts, have invented an Improvement in Casting Copper Tubes, &c.; and I do hereby declare that the following, taken in connection with the drawings which accompany and form part of this specification, is a description of my invention, sufficient to enable those skilled in the art to practise it.

This invention relates, principally, to the manufacture of copper tubes or cylinders, by the process of casting in vertical moulds, the object of the invention being to cheapen and perfect the process of casting, and to obtain thereby copper tubes equal, if not superior, to such as are made by the processes now in use.

The invention is applicable to the manufacture of other than copper tubes, though intended principally for the production of this particular article of manufacture.

The improvement consists in the employment of a cast-iron ring or stay-piece, (technically known as a "bit,") to support and centralize the core in position, with respect to the mould.

Also, in the application of a mouth-piece to the mould, in such manner that the molten metal shall flow into the mould below the bit.

Also, in the combination with this construction of a means for dividing the metal, as it is poured into the mouth-piece, and before it enters the mould.

Patent No. 24,915 was granted to Freeborn Adams for an improvement in casting copper tubes, the process therein described being practised with some success, but not producing uniformly perfect castings. In said process, a rotary mould is employed, and as it is not always practicable to effect this rotation, my invention has particular reference to the construction of a stationary mould, though applicable, in part, to a rotary mould.

Patent No. 32,169, also, was granted to said Adams, in which a stationary mould is employed, the molten metal being poured in two streams, at the top, and upon opposite sides of the mould; but, in my invention, I pour in upon one side only of the stationary mould, and this in such way that the stream enters the mould below the bit, and is divided before it reaches the mould, falling in two streams, which may, however, unite upon the opposite sides of the core.

Figure 1 shows a vertical section, and

Figure 2, top view of a vertical mould, embodying my invention.

Figures 3 and 4 show similar views of a rotary mould, embodying that part of the invention applicable thereto.

a denotes the vertical mould.

b, the hollow core-tube.

In this process of casting, as practised heretofore, this tube is sustained in central position, with respect to the mould, by thin wrought metallic straps, made of hoop-iron, or of thin sheet-copper, and passing around the core, with extensions at their opposite ends, from the core to the mould.

The flexibility of these straps, or stay-pieces, causes the core-tube to be sometimes thrown out of centre, with respect to the mould, thereby producing a casting of uneven thickness.

Moreover, in pouring in the metal against such a bit, the action of the hot metal, and the flames and gases therefrom, tend to oxidize or melt the material of the strap, and quickly destroy it, the particles being carried into the casting, and having afterwards to be cut out.

Where a thin copper bit is employed, the contact of the hot metal soon fuses and destroys it, the use of such copper bits being thereby rendered very expensive, and their want of rigidity making them unreliable for the proper support of the core, and the production of castings of uniform thickness.

Other disadvantages arise from the use of these thin straps, unnecessary herein to specify.

I employ, instead thereof, a cast-iron cylindric ring or bit, *c*, having struts or projections *d*, which support the ring and core in position, the rigidity of the metal keeping the core properly centred, under all circumstances.

In pouring in the molten metal at the top of the mould, it frequently rises above the lower edge of the bit, and, with a wrought-iron bit, which cannot be remelted with the scrap cut off from the casting, it has to be broken out in pieces, whereas the cast-iron bit can be easily detached, without breaking or melting from the top of the casting.

In the stationary mould, however, I obviate the necessity of pouring the fluid in at the top, by the employment of a lateral mouth-piece or spout, *e*, so arranged, in connection with the bit, that the molten metal, poured into the spout, enters the mould below the bit, and without contact, or material contact, therewith.

In combination with this mouth-piece, I place a projection or bar, *f*, in the mouth-piece or spout, and just at or near the entrance of the spout into the mould, in such manner as to divide the liquid stream, (before it reaches the mould, or strikes the core,) so that it shall descend into the mould in two distinct and separate streams, neither of which shall come into contact with the bit or stay-piece *c*.

The core-tube is to be covered with moulders' sand, and the mouth-piece may be lined, and the pin *f* covered with plumbago; but as neither of these things,

nor the manner of supporting the core-tube on its base, form parts of my invention, they need not be particularly described.

In respect to the patents of the aforesaid Freeborn Adams, (one being dated April 30, 1861, and the other, August 2, 1859, the earlier being for a new manufacture of copper-cylinders, and the latter being simply for pouring fluid metal, in two or more streams, into the mould, on opposite sides of it,) I would remark, that I make no claim to the subject of either of such patents, or to any device or devices described in either of them, as my invention does not involve the pouring of the fluid metal, in two or more streams, into the mould, on opposite sides thereof.

In using my mould, the metal is poured in one stream into the mould-nose or spout, on one side of the mould, and is there divided into two streams, which are caused to flow into the mould below the core-supporter, and so as to meet one another on the opposite side of the mould; and I accomplish this by a nose or spout, and a current-cutter, arranged together, and on one side of the mould, in manner as described, each being essential to the other; and, therefore, I make no claim to the arrangement of two current-dividers in the mouth of the mould, as shown in the said Adams's patent, of 1861, for, when they are used, they produce

two currents, which drop into the mould on two opposite sides of it, and simply spread laterally in opposite directions, toward one another, after they may have descended into the mould.

The spout renders it necessary to pour the metal in one current only into the mould, and on one side of it only, and, by having the divider in the spout, the two branches of the current are made to meet at the back, or opposite side of the mould, and the useful effect desired is fully produced.

My invention saves the labor and expense of pouring, at once, from more than one pot or ladle into the mould.

I claim—

The combination and arrangement of the current-divider *f*, with the nose-piece or spout *e*, and the mould *a*.

Also, the arrangement of the current-divider *f*, the spout *e*, the stay-piece *c*, the mould *a*, and the core *b*.
In witness whereof, I have hereunto set my hand,
this 22d day of April, A. D. 1865.

JAMES F. GUTHRIE.
